UNITED STATES PATENT OFFICE.

SAMUEL H. BARTLETT, OF NEW YORK, N. Y.

PORTABLE GALVANIC BATTERY.

SPECIFICATION forming part of Letters Patent No. 228,972, dated June 22, 1880.

Application filed January 23, 1880.

To all whom it may concern:

Be it known that I, SAMUEL H. BARTLETT, of the city, county, and State of New York, have invented an Improvement in Portable 5 Galvanic Batteries, (Case A,) of which the following is a specification.

The object of this invention is to enable a galvanic battery, including the liquid used therewith, to be carried on the person without 10 danger or inconvenience, and without any material hinderance in quickly applying the battery to use.

The said invention comprises a battery-cell fitted with the usual zinc and carbons, in combination with a closed reservoir attached to 15 one end of the aforesaid cell, and communicating therewith by an opening midway, or thereabout, of the depth of the cell, said opening being provided with a suitable plug 20 or valve for the closing of the opening when occasion requires.

In order to use the apparatus as thus constructed the reservoir is filled with any of the usual exciting-liquids, and the opening is 25 closed, as hereinbefore explained, whereupon the apparatus may be carried either upon the person or in a valise, trunk, or the like without danger of spilling the liquid.

When the battery is to be applied for actual 30 battery purposes the plug is removed, the apparatus is turned into a horizontal position, and one-half, or thereabout, of the exciting-liquid passes into the cell, and by submerging the zinc and carbons to the requisite degree 35 puts the battery in operation.

Figure 1 is a plan view, and Fig. 2 a vertical central longitudinal sectional view, of an apparatus embracing my said invention.

A is the cell, fitted in the usual or any suita-

ble manner with the zinc B, the carbons C, 40 and wires appropriately connected with the poles of the battery. At one end of the cell, and rigidly affixed thereto, is the reservoir D, which is entirely closed except for the opening a, which is situated midway, or thereabout, 45 of the depth of the cell, and, of course, of the reservoir. A suitable plug, b, or in lieu thereof, of a valve of any appropriate construction, is provided for this opening.

When the exciting-liquid is placed in the 50 reservoir, and the opening is closed with the plug or its equivalent, it is manifest that the exciting-liquid will, so to speak, be bottled up, and cannot be spilled during any ordinary movement or transportation of the apparatus. 55 On the other hand, when the plug is removed and the apparatus placed in a horizontal position the liquid will flow out into the cell, and by filling the lower part thereof, and to a corresponding extent submerging the zinc and 60 carbons, will put the battery in operation.

It is, of course, to be understood that the cell, together with the reservoir and the plug, is to be made of vulcanized india-rubber or other material practically incorrosive from contact with the exciting-liquid. 65

What I claim as my invention is—

A galvanic-battery cell having attached thereto a reservoir, D., communicating with said cell by an opening midway, or thereabout, 70 of the depth of the cell, and provided with a suitable plug or valve for closing the reservoir when required, all substantially as and for the purpose herein set forth.

SAMUEL H. BARTLETT.
